UNITED STATES PATENT OFFICE.

THOMAS F. CÔTÉ, OF PRINCE ALBERT, SASKATCHEWAN, CANADA.

FUSE-PLUG.

1,198,193.

Specification of Letters Patent. Patented Sept. 12, 1916.

Application filed October 13, 1914. Serial No. 866,491.

To all whom it may concern:

Be it known that I, THOMAS F. CÔTÉ, a subject of the King of Great Britain, residing at Prince Albert, in the Province of 5 Saskatchewan and Dominion of Canada, have invented certain new and useful Improvements in Fuse-Plugs; and I do hereby declare the following to be a full, clear, and exact description of the invention, such as 10 will enable others skilled in the art to which it appertains to make and use the same.

My invention relates to improvements in electric fuse plugs and has for its primary object to improve and simplify construction 15 of such devices, increase the efficiency and reduce the cost of manufacture.

Another object of importance is to provide a fuse plug in which the parts are so assembled as to be readily disassembled to provide 20 for the renewal of parts which may have become broken or deranged and which is provided with means whereby the fuse wire may be readily inspected without necessitating removal of certain parts of the device.

25 Another object is to provide novel means for supporting and operatively connecting the fuse wire with the contacting points of the plug.

The above and additional objects are accomplished by such means as are illustrated 30 in the accompanying drawings, described in the following specification and then more particularly pointed out as claimed.

With reference to the drawings, wherein 35 I have illustrated the preferred embodiment of my invention as it is reduced to practice and throughout the several views of which similar reference numerals designate corresponding parts, Figure 1 is a side elevation 40 partly in section of the improved plug, and Fig. 2 is a detail fragmentary vertical sectional view taken on the plane of line 2—2 of Fig. 1.

Referring to the drawings by characters 45 of reference, 1 designates a frusto-conical base that is provided centrally with a threaded bore in which is mounted a metallic and threaded sleeve 2. The sleeve 2 is provided at its inner end with an annular flange 2^a 50 which flange is arranged to engage upon the inner face of the base 1 and prevents accidental removal of the sleeve. A flange 2^b is provided at the outer end of the sleeve 2 to prevent inward movement of the sleeve. 55 Turned within the sleeve 2 is a threaded metallic plug 3 that is provided with a bevel

60 enlarged head 4 that is grooved and is formed similarly to a screw head. This plug 3 is so positioned that the head 4 projects from the outer face of the base and serves to form a contact with the socket, not shown, in which the plug is to be attached. A threaded opening 5 is formed in the inner end of the plug 3 and receives a fastening screw 6.

65 Suitably secured to the inner part of the base 1 is a tapered hollow body 7 that is formed of some suitable insulating material such as porcelain and the like. The outer face of this body 7 is threaded and has mounted thereon a metallic and threaded sleeve 8 which is tapered and snugly fits the body 7. The sleeve 8 is spaced at its outer end from the outer end of the body and said body is provided at a point adjacent to 70 the outer end of the sleeve with an annular bead 9. Formed on the body 7 at a point next adjacent to the bead 9 is a laterally projecting annular flange 10. The outer end of the body 7 is open and is designed to be 75 closed by a circular glass plate 11 which overlaps the edges of the open end and is secured in position by an annular flange securing ring 12. The ring 12 is provided at its inner and outer edges with annular 80 depending flanges 13 and 14 which space the ring from the body, and engage the plate 11 for holding the same in position.

85 The flanges 13 engage the outer face of the plate 11 at a point adjacent to its periphery and securely hold the same in position. The flange 14 is slightly curved at the point of its formation with the ring and engages upon the outer face of the flange 10 at a point adjacent to its periphery. The 90 flange 9 is provided with an upstanding annular enlargement or projection 15 and said enlargement or projection 15 is engaged upon its outer face by the flanges 14. Split pins 16 are inserted through the ring 12, projection 15 and flange 9 and have their inner terminals bent angularly as at 17 so as to prevent withdrawal of the pins accidentally. These pins securely hold the ring 12 in position.

100 The vertical portion of an L-shaped contact member 18 is soldered or otherwise suitably connected as at 19 with the metallic casing or sleeve 8 and has its horizontal portion extended through an opening in the 105 body 7 and into the interior thereof. A screw 20 is turned in the free end of the 110

horizontal portion of the L-shaped contact member.

Mounted within the body 7 is a fuse wire 21 of the usual type and which has its ends secured by the screws 6 and 20. By means of the screws 6 and 20 carried respectively by the plug 3 and contact member 18, the fuse 21 may be supported in the desired position and in spaced relation to the walls of the body. The contact is made through the medium of the metallic sleeve 8 and contact member 18 which is preferably formed of copper and through the plug 3.

It will be readily seen that I have provided a simply constructed fuse plug that may be readily assembled and disassembled for the purpose of renewing the fuse wire or other parts which may have become broken or deranged. The glass plate 11 permits inspection of the wire to ascertain as to its condition and it is only necessary to remove the pin 16 and ring 12, and then the plate 11 to gain access to the wire 21.

In practice, I have found that the form of my invention, illustrated in the drawings and referred to in the above description, as the preferred embodiment, is the most efficient and practical; yet realizing that the conditions concurrent with the adoption of my device will necessarily vary, I desire to

emphasize the fact that various minor changes in details of construction, proportion and arrangement of parts may be resorted to when required, without sacrificing any of the advantages of my invention, as set forth.

What is claimed is:—

In a fuse plug having one end of its body provided with a laterally projecting annular flange, said flange provided on its upper face with an upstanding annular enlargement forming annular grooves on opposite sides of the flange, a glass closure plate seated in the inner groove of the enlargement closing the opening of the body, an annular ring having depending inner and outer flanges, the inner flanges of ring engaging the upper face of the glass plate, the outer flange of the ring engaging in the outer groove of the annular enlargement, and a plurality removable fastening elements extending through the ring and the enlargement and the flange of the body holding the ring and plate in position.

In testimony whereof I affix my signature in presence of two witnesses.

THOMAS F. CÔTÉ.
